UNITED STATES PATENT OFFICE

JAMES E. MCINTIRE, OF PEABODY, MASSACHUSETTS, ASSIGNOR TO UNITED SHOE MACHINERY CORPORATION, OF PATERSON, NEW JERSEY, A CORPORATION OF NEW JERSEY

FOLDING MACHINE

Application filed June 5, 1925. Serial No. 35,111.

This invention relates to folding machines and is herein illustrated as embodied in a machine for folding the margins of the covers of book cases and similar articles.

In the manufacture of memorandum books, pocket books, and similar articles, it is customary to attach to a board or backing of paper or cardboard by means of paste a cover of leather, imitation leather, cloth or the like the margins of which extend beyond the edges of the backing; and then to apply paste to these margins and fold them over upon the adjacent margins of the backing. The corners of covers of the kind referred to are commonly of two types, rounded and square, the present invention being concerned more particularly with the folding of covers the corners of which are rounded. Such corners should be evenly plaited so that the folded-over margin may be as flat as possible and the folded edge have a smooth contour.

In order to ensure such even plaiting, there are provided, according to one feature of the invention, a work support, a forming block and a folder, the two last-named elements being adapted in the illustrated machine to move in a path which is substantially parallel to the surface of the work support and, to grip between them the small evenly spaced puckers which are formed when the folder gathers the margin of the work about the block, and thus to prevent the puckers from becoming displaced and thereby resulting in uneven plaits in the finished work. In the illustrated machine, the work is placed upon the work support and the margin at a corner thereof bent upwardly, said upstanding margin lying between the block and the folder. The folder then moves over the work support and in so doing first gathers the corner of the cover about the rounded face of the block thereby forming small, evenly spaced puckers in said margin and pressing the puckered mar-

gin against the block. Thereafter, as the folder continues its movement to fold the margin over the body portion of the cover, the block, which is yieldingly mounted for movement in the same direction as the folder, is pushed along by the folder and continues to exert pressure all the time upon the puckered margin so as to prevent the puckers from becoming displaced and uneven. With this construction and mode of operation the small, evenly spaced puckers are converted into small, evenly spaced plaits so that the folded over margin is as flat as possible and the folded edge has a smooth contour.

The round cornered boards or backings used vary greatly in stiffness. When such board is made of cardboard or other stiff material, it is possible to fold the margin of the cover directly over the edge of the board; but, when the board is thin and weak, it is difficult to make a satisfactory fold in this manner. According, therefore, to another feature of the invention, a former, which may be a thin suitably shaped plate, is provided over which the margin of the cover may be folded to define the line of fold, the forming block being mounted for sliding movement in a path substantially parallel to the surface of the forming plate.

These and other features of the invention will be described as embodied in an illustrative machine and pointed out in the appended claims.

Referring now to the accompanying drawings,

Figure 1 is a perspective of a machine in which the present invention is embodied; and

Figures 2 to 12 inclusive are perspectives of the work-engaging parts of the machine in various positions which they occupy during the operation of the machine, a piece of work being shown in each instance in process of being operated upon.

Referring first to Figs. 2 to 12, the illustrative machine is particularly adapted to the folding of the covers of book cases and similar articles having rounded corners, such work commonly comprising a backing 100 of cardboard paper or other suitable material and a cover 200 of flexible material which is commonly leather, imitation leather or cloth, the cover being larger than the backing so that its margin projects beyond the edge of the backing. A coating of paste is applied to this projecting margin, after which the margin is folded over and pressed down upon the margin of the backing. Where rounded corners are desired, the backing is cut with rounded corners and the cover with similarly rounded corners or with partially cut off square corners; and, when the corner of such a cover is folded over the corner of such a backing, the corner of the cover should be evenly plaited so as to lie as flat as possible.

Before giving a detailed description of the illustrative machine, a brief description of its mode of operation will be given. Referring first to Fig. 1, the machine comprises two mechanisms, a corner folding mechanism for folding round corners, and a straight-edge folding mechanism for folding the edges which lie between the corners. The straight-edge folding mechanism comprises a table 13 and a folder 19. The corner folding mechanism comprises a generally triangular table 17, a folder 19, a forming plate 21, in the form of a thin, generally triangular plate, and a forming block 23. In the operation of the machine, the corner of the work is placed upon the table 17 with the projecting margin of the cover extending over an edge guide 25 and with the work properly located by corner guides 27 which may engage the straight edges of the backing adjacent to the corner. These corner guides may be first raised to permit the margin of the cover to be thrust beneath them and then allowed to fall, so that the work may be properly located by causing the guides to engage the straight edges of the backing adjacent to the corner. The forming plate 21 is brought down by a treadle 40 to press the work firmly upon the table 17 and thereby to cause the projecting margin of the cover to be bent upwardly, and then a one-revolution clutch is rendered operative with the following results: The folder 19 moves forward to fold the upwardly bent margin of the corner of the cover over the edge of the forming plate 21, the forming plate is withdrawn from beneath the folded over margin of the cover, and the table 17 rises to press the fold against the under surface of the folder. The parts then return to the positions shown. After the corners of the cover have been folded in succession, the straight edges are presented in succession upon the table 13, and the straight-edge

folder 19 folds over the margin of the cover after which the table 13 rises to press the fold. As thus far described, the machine is substantially the same as that disclosed in application Ser. No. 729,930, filed Aug. 4, 1924, in the name of Glass and owned by the same assignee as is the present invention.

The invention will now be described in detail in connection more particularly with Figures 2 to 12 from which the corner guides 27 have been omitted to promote clearness. Figures 2 and 3 show the work as it appears just after the forming plate 21 has descended to cause the margin of the cover 200 to be bent upwardly. The two parts of the folder 19 then swing toward each other about their pivots 29 and simultaneously move forward to gather the corner of the cover in small, evenly spaced puckers about the forming block 23, this gathering taking place progressively. In the position of parts shown in Figures 4 and 5, the parts of the folder 19 have swung toward each other to an extent and moved forward sufficiently to cause the upstanding margin at the corner of the cover to approach fairly close to the reduced lower portion of the block. In the position of parts shown in Figures 6 and 7, the parts of the folder have swung completely together and moved forward sufficiently to gather the corner of the margin of the cover about and press it firmly against the block. It should be noted that the block 23 is normally located near the rounded forward end of the forming plate 21 and has a convex rounded surface about which a concave complementary recess in the folder 19 gathers the upstanding margin of the cover when the parts reach the positions shown in Figures 6 and 7 to form the small, evenly spaced puckers which have been referred to above. As the folder continues to move forward into its successive positions, one of which is shown in Figures 8 and 9, the margin of the cover is folded over the edge of the forming plate 21, the block 23 being pushed to the left against the force of a spring 31. During this folding of the margin over the edge of the forming plate the margin is gripped yieldingly between the block and the folder so that the puckered margin, which resulted from the movement of the folder into the position shown in Figures 6 and 7, is drawn or dragged between the opposed gripping surfaces of the forming block and the folder. After the folding of the margin of the corner of the cover over the forming plate has been completed, the forming plate is withdrawn from beneath the folded-over margin as shown in Figures 10 and 11. The table 17 then rises to press the fold against the under side of the folder 19, the forming plate 21, and with it the block 23, is raised to initial position, and the machine comes to rest with the parts in the positions shown in Figure 2.

When the margin at the corner of the cover is gathered about the block 23 in the manner shown in Figures 6 and 7, puckers are formed, as has been explained, which are small and substantially evenly spaced; and these puckers are prevented from becoming disarranged during the folding operation by reason of the fact that they are gripped between the block and the folder during the completion of the folding operation in the manner which has been described.

It has been stated above that small evenly spaced puckers are formed in the margin of the work when said margin is gathered about the forming block by the folder. In the illustrated construction of forming block which is particularly adapted to leather covers it will be noted that this block has not only a rounded portion which faces the folder but an upwardly and outwardly flaring portion. This upwardly and outwardly flaring portion is particularly desirable when the cover is made of soft and very flexible material such as leather. Under these circumstances the outwardly flaring upper portion of the forming block spreads the upper portion of the margin out somewhat so as to tend to prevent the formation of puckers in this portion at the stage illustrated in Fig. 7, the puckers being formed in the locality engaged by the folder and progressively flattened by the folder into plaits almost immediately after they are formed. It should also be noted that with a forming block having this upwardly and outwardly flaring portion, the margin is bent into a reverse curve (see Fig. 7) so that it is gripped more strongly than would otherwise be the case between the folder and the forming block and is consequently pulled tightly over the edge of the forming plate.

The forming plate 21 is carried at the lower end of a stem 33 the split hub of which is fastened by a pinch screw 35 to a rod 37 which is slidably mounted in a carrier in the form of a sleeve 39, the rear or right-hand end of the rod 37 carrying a block presently to be referred to, which travels in a track cam 115 (see Fig. 1). In order to prevent the block from chattering in its cam track, the rod 37 is urged to the left by a coiled spring 41 which bears at one end against the end of the sleeve and at the other end against a collar 43 which is adjustably fastened by a set screw to the rod.

The forming block 23 is fastened to a small rod 45 which is slidably mounted in the stem 33, and said block has a flat under side which rests upon the flat upper face of forming plate 21. The block 23 is adjustably fastened to the rod 45 by a set screw 47, said rod being urged continually to the right by the tension spring 31 which is fastened at one end to an eye bolt 51 in the stem 33 and at the other end to a small bracket 53

adjustably held in place on the rod 45 by clamping nuts 55 so that the tension of the spring may be varied. The extent to which the rod 45 is permitted to move to the right is limited by a stop 57 in the form of a collar threaded upon the rod and adapted to contact with the stem 33. The right-hand end of the rod 45, which is turned down somewhat, is adapted to contact, when the folder 19 has moved forward to about the position shown in Figures 6 and 7, with an abutment in the form of a hardened block 59 fastened by a screw 61 to the slide member 63 to which the members of the folder 19 are pivoted. The force with which the margin of the cover is pressed against the block 23 during the folding operation thus depends upon the position occupied by the block 23 on the rod 45, provision being thus made that thicker or thinner materials may receive the same or different pressures as may be desired.

Any suitable mechanisms may be employed for imparting to the corner guides 27, the former 21, the two-part folder 19 and the table 17 the movements which have been described above. The particular mechanisms shown in the illustrative machine are the same as those of application Ser. No. 729,930, which has been referred to above, the details of their constructions forming no part of the present invention. These mechanisms will, therefore, be described very briefly in a general way.

The corner guides 27 are normally in their lowered position, as shown in Figure 1. They must be raised slightly to permit the margin at the corner of a cover to be presented beneath them, then allowed to descend into lowered operative position so as to engage the edges of the backing 100 adjacent to the corner thereof so that the work may be properly positioned, then raised and held raised during the folding operation, and finally permitted to descend to the position shown. These corner guides 27 are carried at the outer ends of arms 65 having a common hub which is fast to a rock-shaft 67. The rock-shaft has fast to it two arms 69, 71 carrying rollers at their outer ends. Cooperating with the roller on the arm 69 is a lever 72, pivoted to the frame at 73 and having pivoted to its rear the upper end of a link 75, the lower end of which has a pivotal connection with an arm 77, said arm being pivoted to the frame at 79 and having pivoted to it near its middle portion the upper end of a treadle rod 81. The lower end of this treadle rod is attached to the toe end of a heel-and-toe treadle, not shown, the heel end of the treadle being attached to the lower end of a treadle rod 83, which, as will presently be explained, acts to pull the former 21 down upon the work. In the operation of the machine, the toe end of the heel-and-toe treadle is pushed part way down so as to raise the corner guides

27 slightly while the operator is placing the corner portion of the cover upon the table 17, and is then released to permit the corner guides to fall into operative position. The 5 operator now locates the work properly with the aid of the corner guides. He next depresses the heel end of the treadle whereupon, as will presently appear, the former 21 is brought down and locked in the position 10 shown in Figure 2. He then pushes the toe end of the treadle all the way down and releases it. Pushing the treadle all the way down throws in a one-revolution clutch, not shown, which causes the shaft 85 to make one 15 revolution and come to rest. This one revolution of the shaft through a master cam and levers, not shown, causes the slide 63 which carries both the corner folder 19 and the straight-edge folder 15 to move forward, to 20 pause and then to return to the positions shown. As this slide moves forward, a beveled block 89 lifts the arm 71, and with it the corner guides, holds them raised during the folding and fold-pressing operations and 25 finally permits them to fall into the position shown in Figure 1. The tables 17 and 13, like the folders 15, 19, are operated in unison from the master cam on the shaft 85 to press the folds and to release them at the proper 30 time.

As has been stated, depression of the heel end of the treadle to cause a downward pull on the rod 83, pulls down the former 21 to press the work against the table 17. This 35 rod is pivoted at its upper end to the middle portion of an arm 89 which is pivoted to the frame at 91, said arm having pivotally connected with its outer end the lower end of a link 93, the upper end of which is pivoted to the outer end of an arm 95 the hub of which is fast to one of a pair of alined rock-shafts, the common axis of which is indicated at 97. Fast 40 respectively to these alined rock-shafts are hubs 99, 101 at the ends of the arms of a fork which is integral with the sleeve 39 in which, as has been explained, is slidably mounted the rod 37 to the outer end of which the stem or carrier 33 of the former 21 is fastened. A spring-pressed plunger 103, mounted in a casing 105 which is integral with the arm 95, normally holds the parts in 45 the positions shown with the former 21 and block 23 raised above the table 17; and a catch, indicated as a whole by the numeral 107, is adapted to hold the sleeve 39 and with it the former in lowered position during the folding operation, said catch being tripped at the proper time by a roll at the upper end of 50 an arm 109, said arm being actuated by the same master cam on the shaft 85 which operates the folders and the tables.

The operation of the machine is briefly as follows:—The toe end of the heel-and-toe 55 treadle, which is attached front and rear re-

spectively to the treadle rods 81 and 83, is depressed enough to raise the corner guides 27 somewhat above the table 17 but not enough to start the one-revolution shaft 85. A piece of work, comprising a backing 100 and a cover 200 to the projecting margin of which a coat 70 of cement has been applied, is presented beneath the corner guides and the toe end of the treadle released to permit the corner guides to fall. The work is now manipulated to cause 75 the corner guides to contact with the straight edges of the backing adjacent to the corner. The heel end of the treadle is depressed to pull down the arm 95 and with it the sleeve 39 so as to cause the forming plate 21 to press 80 the work against the table. The arm 95 is locked in its lowered position by the catch 107 and the forming plate 21 thus held down during the operations illustrated in Figures 85 2 to 11. The toe end of the treadle is then depressed to its full extent and released. This imparts one revolution to the shaft 85 and causes the following movements. The folder slide 63 moves forward, as shown in Figures 90 4 to 11, and causes the two parts of the folder 19 to move forward and to swing about their pivots 29 by reason of the fact that the upper ends of pins 111 carried by the tails of the folder parts run in suitably shaped grooves formed in the under side of a cover plate 113 95 (Fig. 1). The cam track member 115 (Fig. 1) in which runs a block pivoted to the rear end of the rod 37 which carries the forming plate 21, is then swung bodily forward to move the forming plate 21 out from beneath 100 the folded over margin of the cover, as shown in Figure 11. The catch 107 which holds the forming plate carrier 39 down is tripped by the arm 109, and the table 17 raised to press 105 the fold, as shown in Figure 12, and finally 105 the parts return to their normal positions as shown in Figure 1.

The four corner portions of the work are presented in succession to the corner folding mechanism, which has been described above, 110 and then the four straight-edge portions of the work are presented to the straight-edge folding mechanism comprising the table 13 and folder 15 (Fig. 1). Although it is stated above that the corners are folded first and 115 then the straight edges this order of procedure may be reversed, if desired, by folding the straight edges first up to points spaced from the corners and then folding the corners. 120

Although the invention has been set forth as embodied in a particular machine, it should be understood that the invention is not limited in the scope of its application to the particular machine which has been shown and described. 125

The general organization of the illustrated machine and the broad combination with a folder of a forming block are not claimed herein but form the subject matter of prior 130

applications, Serial No. 656,557 filed Aug. 9, 1923, in the name of Glass, and Serial No. 729,930 filed Aug. 4, 1924, also in the name of Glass, both of these applications being assigned to the same assignee as is the present application.

Having thus described my invention, what I claim as new and desire to secure by Letters Patent of the United States is:—

- 10 1. A machine of the class described having, in combination, a work support, a folder movable over the work support in a direction substantially parallel to the plane of said support, a cooperating forming block about 15 and against which the margin of the work is held by the folder during the folding operation, said block being mounted for movement in the same direction as the folder, and means operating prior to the movement of 20 the folder for holding the block stationary in the path of movement of the folder.
2. A machine of the class described having, in combination, a work support, a folder movable over the work support in a path substantially 25 parallel to the plane of said support a cooperating forming block mounted for movement in the same direction as the folder, means operating prior to the movement of the folder for holding the block stationary in the path of movement of the folder, and means for imparting movement from the folder to the block.
3. A machine of the class described having, in combination, a work support, a folder movable over the work support in a path substantially 30 parallel to the plane of the surface of the support, a co-operating forming block located in said path of movement and mounted for movement in a path which extends in the same direction as that of the folder, and means for causing the margin of the work to be yieldingly clamped between the block and the folder during the folding operation.
4. A machine of the class described having, 35 in combination, a work support, means for bending upwardly the margin of the work a forming block, a folder and means for causing the folder and block to grip the margin and to move in unison in the same direction 40 to fold the margin over the body portion of work.

5. A machine of the class described having, in combination, a support for the work, means for bending up the margin of the work 45 a folder, means for moving the folder in a path to fold the upturned margin down over the body portion of the work, a forming block mounted for movement in the path of folding movement of the folder and yield- 50 ing means tending to resist movement of the block in said path whereby the block and the folder are caused yieldingly to grip the margin of the cover between them and to move together in the same direction over the body 55 portion of the cover.

6. A machine of the class described having, in combination, a work support, a folder movable over the support, a forming block, a member by which the forming block is carried said member being mounted for sliding movement toward and from the folder, and an abutment movable with the folder and adapted to contact with said member during the movement of the folder.

7. A machine of the class described having, in combination, a work support, a folder movable over the support, a forming block located in the path of movement of the folder, a carrier for the block mounted for yielding movement, means for causing the folder to press the margin of the work against the block during the folding operation, an abutment movable with the folder and arranged to contact with the carrier of the block, and means whereby the initial distance between the block and the folder may be varied to vary the force with which the margin of the work is pressed against the block.

8. A machine of the class described having, in combination, a work support for the corner portion of a piece of work, means for bending upwardly the margin of the work, a forming block having a convexly rounded surface, a folder having a concave recess the outline of which corresponds approximately to that of the rounded surface of the block, and means for moving the folder over the support to fold the upstanding margin over the body portion of the work, said folder acting to gather the margin about the rounded surface of the block and to carry the block with it in its movement, the relative positions of the block and the folder remaining unchanged during the time that the folder and the block are both moving.

9. A machine of the class described having, in combination, a support for the corner portion of a piece of work, means for bending upwardly the margin of the work, a forming block having a convexly rounded surface, said block being located above the support and mounted for yielding movement in a path substantially parallel to the surface of the support, a folder mounted for movement in the same path, said folder having in its operative edge a concave recess, and means for causing the block and folder to grip the upstanding margin and lay it over into a position parallel to the plane of the work.

10. A machine of the class described having, in combination, a support for the corner portion of a piece of work, means for bending upwardly the margin of the work, a forming block having a convexly rounded surface, said block being located above the support and mounted for yielding movement in a path substantially parallel to the surface of the support, a folder mounted for movement in the same path, said folder having in its operative edge a concave recess, means for causing

the block and folder to grip the upstanding margin and lay it over into a position parallel to the plane of the work, and means for pressing the fold between the work support and the folder.

- 5 11. A machine of the class described having, in combination a support for a piece of work, an edge guide, means for bending upwardly the margin of the work at a corner thereof against the edge guide, a folder movable over the edge guide in a path substantially parallel to the plane of the support, a forming block held in the path of folding movement of the folder and mounted for 10 yielding movement in the direction of said movement, means for causing the folder to move over the edge gage first to gather the margin about the block and then to cause the block to move in unison with the folder, and 15 means for causing relative movement or approach between the support and the folder to press the fold.

12. A machine of the class described having, in combination, a work support, a forming plate adapted to rest upon the work, a 25 folder movable over the forming plate in a path substantially parallel to the plane of the forming plate to fold the margin over the plate, and a forming block adapted to be moved by the folder in the same direction.

13. A machine of the class described having, in combination, a work support, a forming plate adapted to rest upon the work, a folder movable over the plate in a path substantially parallel to the plane of the plate to fold the margin over the plate, a forming block adapted to be moved by the folder in the same direction, means for withdrawing the forming plate from the fold, and means 35 for causing the fold to be pressed between the work support and the folder.

14. A machine of the class described having, in combination, a support for the corner portion of a piece of work comprising a backing and a cover the margin of which projects beyond the edge of the backing, an edge guide over which the projecting margin extends when the work is presented to the machine, a forming plate having a rounded corner, 45 means for causing the plate to press the work against the support and thereby to bend the margin of the cover upwardly, a forming block located near the rounded corner of the plate, said block being mounted for yielding 50 movement in a path substantially parallel to the plane of the plate, a folder, and means for causing the folder to press the upstanding margin of the work against the forming block and to move the block in a substantially 55 straight path over the plate.

15. A machine of the class described having, in combination, a work support, a forming plate, a carrier for the plate movable toward and from the work support, a folder 65 movable during the folding operation over

the plate, and a forming block slideable with respect to the plate and located in the path of movement of the folder.

16. A machine of the class described having, in combination, a work support, a forming plate, a member by which the plate is carried, said member being movable toward and from the work support, a folder movable during the folding operation over the plate, and a forming block slideably mounted in the forming plate carrier and located in the path of movement of the folder.

17. A machine of the class described having, in combination, a work support, a forming plate, a folder movable over the forming plate in a path substantially parallel to said plate, and a forming block located in the path of movement of the folder, said block being slideably mounted and having a rounded portion facing the folder and an upwardly and outwardly flaring portion.

18. A machine of the class described having, in combination, a work support, a folder movable over the work support in a path substantially parallel to the surface of the support, and a forming block located in the path of movement of the folder and also movable in a path which is substantially parallel to the surface of the work support, said block having a rounded portion facing the folder and an upwardly and outwardly flaring portion.

19. A machine for folding the margin at the corner of the cover of a book case over the round corner of a board thereof having, in combination, a work support, a forming plate, a folder movable over the forming plate during the folding operation, and a forming block adapted to cooperate with the folder, said block having a flat under surface adapted to rest upon the plate, and means for mounting the block for sliding movement.

20. A machine for folding the margin at the corner of the cover of a book case over the rounded corner of a board thereof having, in combination, a support for the work, a folder movable over the support, a forming block between which and the folder the margin of the cover is frictionally gripped during the folding operation, and means for varying the normal relation between the folder and the block to vary the force of the gripping action.

21. A machine for folding the margin at the corner of a book case over the round corner of a board thereof having, in combination, a folder movable in a straight path and having an operative face adapted to engage the outer face of the margin, a forming block having an operative face to engage the inner face of the margin at a locality opposite to that engaged by the folder and also movable in a straight path, means for holding the forming block with a portion of its operative

face located in the path of movement of the operative face of the folder, and means for causing the folder to be moved until its operative face is spaced a predetermined distance from the operative face of the block and for thereafter causing the block to be moved with the folder, the two operative faces being maintained in opposed relation during the folding operation.

10 In testimony whereof I have signed my name to this specification.

JAMES E. McINTIRE.
